UNITED STATES PATENT OFFICE.

PAUL MANSEL, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

TIME STAMP.

Application filed January 11, 1922. Serial No. 528,569.

To all whom it may concern:

Be it known that I, PAUL MANSEL, a citizen of the German Empire, residing at Berlin-Charlottenburg, Germany, have invented certain new and useful Improvements in Time Stamps, of which the following is a specification.

This invention relates to time-stamps, the time printing wheels of which are mounted 10 in a reciprocating stamping frame, which carries also electromagnets, receiving at regular time intervals current impulses controlled by an electric clock and actuating the time printing wheels.

15 The object of the invention consists in the design of such a time-stamp, which is simple in construction and which may be manipulated as the usual hand time-stamp with manual control of the time printing wheels.

20 A principal feature of the invention consists in the arrangement of an ink pad in the lower part of the base frame in such a manner that at the downward motion of the stamping frame, the pad is engaged by 25 the type wheels and moved also downwardly for a certain length of way and then rotated around an axis provided at the base frame, so that the time printing wheels can freely perform their downward stroke 30 for stamping purposes. By this arrangement, ink rollers such as are usual in apparatus of this kind are avoided and a better inking of the types is obtained.

Another feature of invention consists in 35 the arrangement and operation of the locking pawls for preventing undue rotation of the time printing wheels. At present in apparatus of this kind two sets of locking pawls are used, one of the sets being pressed by 40 springs against the ratchet wheels pertaining to the time printing wheels and the other set being moved positively into and out of locking position. For doing away with one of the sets of pawls according to the invention the 45 spring pressed pawls are secured in their locking position also by means of a crossbar connected positively with the armature of the electromagnets, so that it is moved with the latter into and out of locking position.

50 A further feature of invention consists in the attachment of the electromagnets to the detachable upper crossbar of the reciprocating frame, this crossbar forming the yoke of the electromagnet and carrying also 55 the handle for manipulating the time-

stamp. The electric appliances of the stamp may be thus withdrawn on detaching the cross-bar as a whole from the reciprocating frame, so that all the electric parts are freely accessible. Further the area in 60 transverse direction required by the vertically arranged electromagnets is not greater than that required by the counting and time printing wheels, so that a compact design 65 of the stamp is obtained.

A time-stamp designed in accordance with the present invention is shown in Figs. 1 and 2 of the accompanying drawing, which figures represent two longitudinal sections of the stamp. Figs. 3 and 4 represent full views of the two broad sides of the lower portion of the stamp.

Shape and size of the new stamp are similar to those of the usual manually adjusted stamps. It has a reciprocating stamping 75 frame 1, arranged within an outer base frame 2. The upper crossbar of the reciprocating frame is provided with a handle 3. In the handle is mounted a spring 4, for cushioning the downward stroke and for 80 automatically drawing back the reciprocating frame. The spring 4 rests with its lower end on a rod 5 connected to crossbar 6, which is fixed to the base frame and arranged within longitudinal slots 6' of the 85 reciprocating frame. In the base frame is mounted an ink pad 7, which is rotatably arranged on an axis 8. This latter is supported by the free ends of arms 10 pivoted to the base frame. Springs 9 are connected 90 at one end with these arms, and fixed at their other end to the base frame. The pad box carries at its bottom face two pivoted arms 11, connected with each other by a spring 11' and resting on pawls 12, pivoted 95 to the base frame 2 and connected by a spring 13 with each other.

In the reciprocating stamping frame are mounted electromagnets 14, connected by conduits 14' led through a channel 14'' in 100 the handle 3 to an electric controlling clock not shown in the drawing. The electromagnets 14 are fixed to the detachable upper crossbar 15 of the reciprocating frame. The crossbar forms the yoke of the electromagnets. The armature 16 of the electromagnet is connected by coupling rods 17 with an oscillating frame 19 loosely supported by the axis 18 of the type wheels. The ratchet wheels 18' pertaining to the 110

printing wheels 18' are engaged and rotated in a well known manner by progressing pawls 19' mounted in the frame 19, which embraces the time printing wheels. Details 5 of this arrangement are shown, for instance, in the U. S. Patent No. 916,001.

In order to prevent an undue rotation of the time printing wheels, while they are in contact with the pad, they are locked by 10 locking pawls 20 pressed by springs 21 against the ratchet wheels. However to positively secure the time pointing wheels against rotation, positively actuated locking means are further necessary. To that purpose, a crossbar 22 is provided according to 15 the invention, which is fixed to the coupling rods 17. In the position of rest shown on the drawing this crossbar rests upon the locking pawls 20 and prevents any movement 20 of the same. When the armature however is attracted on the excitation of the electromagnet by a current impulse for progressing the time printing wheels, the crossbar 22 is withdrawn from the locking pawls 20 so that 25 this latter may yield to the pressure exercised by the advancing pawls 19' on the ratchet wheels 18'.

The advancing of the trains of wheels 23 of the counter is performed in the following 30 well known manner.

A stop 24 provided at the base frame 2 and projecting through a slot of the reciprocating frame 1, engages an oscillating frame 19^a, carrying the feeding pawls of the 35 counter wheels. In the position of rest a spring 25 connected to the reciprocating frame 1 and the oscillating frame 19^a is thus stretched. By moving the reciprocating frame 1 downwardly for stamping purposes, the frame 19^a is withdrawn from the stop 24 and rotated by the stress of the 40 spring 25. When the reciprocating frame returns to its upper position, the stop 24 engages again the oscillating frame 19^a and 45 this latter is rotated in the opposite direction, whereby the feeding pawls rotate one of the numeral wheels of the counter in the same manner as the rotation of the time printing wheels is performed by the feeding 50 pawls 19'.

For stamping the reciprocating frame is moved downwardly by means of the handle 3. The printing wheels engage the ink pad which is also moved downwardly until the 55 locking pawls 12 allow the passage of the arms 11, whereupon the pad is rotated downwardly around the axis 8, so that the passage for the downward motion of the printing wheels becomes free and the stamping operation may be performed. After stamping 60 the reciprocating frame returns automatically under the action of the spring 4 to its upper position and the pad returns by the stress of the springs 9 to its position of rest.

65 Fig. 3 shows one broad side view of the

lower portion of the stamp indicating the opening 2^a provided in the outer frame 2, over which openings the pawls 12 extend transversely, the pawls being drawn together by means of a spring 13, by which they are held against abutment pins 13^a. On the points 12^b of these pawls rest the points 11^b of arms 11. Fig. 3 illustrates the position of the pad before the stamping takes place. Fig. 4 illustrates the other, opposite, broad 75 side of the lower portion of the stamp, with the pad 7 in its position during the stamping operation. The points 11^b can be clearly seen at the ends of arms 11, which arms are held together by tension spring 11^a. The 80 operation of the pad during the stamping is as follows:

The inner frame of the stamp is pushed into the outer frame, the type wheels press 85 against the pad and thereby press the arm points 11^b onto the pawl points 12^a. Since this pressure is vertical, the pawls 12 with the points 12^a yield outwardly to a point at which the points 11^b of arms 11 slide past the points of pawls 12. At this instant 90 spring 13 returns the pawls 12 into the position shown in Fig. 3 in which they abut against pins 13^a. The pad 7 now encounters no more obstructions in its downward swing 95 into a vertical position in which the type wheels become exposed to the surface to be printed. This downward swing is caused by the lower rim of the descending reciprocating frame 1 abutting against the pad casing and swinging it clear of the type 100 wheels against the tension of spring 8^a, which is fastened at one end to the pad casing and at the other end to axle 8. The return motion of the pad is effected by 105 means of torsion spring 8^a. On the return motion of the pad, the points 11^b of arms 11 press against the lower edges of pawls 12, arms 11 are spread outwardly until they 110 slide past the outer points of pawl 12 under the tension of spring 11^a by which they are returned into normal position as shown in Fig. 3. In this normal position the arms 11 abut against stops 11^c which are shown in Fig. 4.

115 While the reciprocating frame is moving upwardly, the advancing of the counter takes place as described. On the excitation of the electromagnets 14 by a current impulse, the armature 16 is attracted, whereby the locking bar 22 is withdrawn from the locking pawls 20 and the frame 19 is rotated by the coupling rods 17 in the direction of the arrow shown in Fig. 2. While the armature returns to its position of rest, the frame 19 is rotated opposite to the direction shown by the arrow, and during this rotation the feeding pawls 19' actuate the time printing wheels in the known manner.

120 When the armature has reached its posi- 125

tion of rest, the locking bar 22 again locks positively the pawls 20 in their locking position.

I claim:—

- 5 1. In a time-stamp the combination with a reciprocating stamping frame and time printing wheels mounted in said frame, of a base frame, an ink pad mounted in said base frame so as to be engaged by said
- 10 10 time printing wheels when said stamping frame is moved downwardly and supporting means for said ink pad allowing a short parallel downward motion of the pad together with said time printing wheels to obtain a good inking of the printing types and hereupon a downward rotation of the ink pad to bring it out of the path of said downwardly moving stamping frame.
- 15 2. In a time-stamp the combination with 20 a reciprocating stamping frame and time printing wheels mounted in said frame, of a base frame, an ink pad mounted in said base frame so as to be engaged by said time printing wheels when said stamping frame is moved downwardly, an axis on which the box of said ink pad is rotatably mounted, lever arms pivoted to said base frame and supporting said axis at their free ends, springs fixed to said base frame and connected to said pivoted lever arms to keep the same in their upper position, lever arms pivoted to the bottom face of said pad box, a spring connected with said lever arms to keep the same apart, spring pawls pivoted to said base frame and supporting the free ends of said lever arms, and being adapted to recede when a pressure is exercised upon the same by said lever arms.
- 20 3. In a time stamp the combination with 40 a reciprocating stamping frame and time printing wheels mounted in said frame of vertically arranged electromagnets fixed to the detachable upper cross bar of said stamping frame, said cross bar forming the yoke 45 of said electromagnets, an armature arranged below said electromagnets in said stamping frame, an oscillating frame embracing said time printing wheels, progress-
- ing pawls mounted in said oscillating frame and engaging ratchet wheels pertaining to 50 said time printing wheels, coupling rods connecting said armature with said oscillating frame, a base frame, an ink pad mounted in said base frame so as to be engaged by said time printing wheels when 55 moving downwardly, said pad being moved downwardly and pushed aside to bring it out of the path of said downwardly moving time printing wheels.
5. In a time stamp the combination with 60 a reciprocating stamping frame, and time printing wheels mounted in said frame, of electromagnets fixed to the detachable upper cross bar of said reciprocating stamping frame, said cross bar forming the yoke 65 of said electromagnets and carrying the handle of the apparatus, channels in said handle for conduits connecting said electromagnets to a current impulse controlling electric clock, an armature mounted in said 70 reciprocating stamping frame below said electromagnets, an oscillating frame embracing said time printing wheels, ratchet wheels pertaining to said time printing wheels, progressing pawls mounted in said 75 oscillating frame and engaging said ratchet wheels, coupling rods connecting said armature to said oscillating frame, spring pressed locking pawls pressed against said ratchet wheels, a cross bar connected to 80 said armature, said cross bar engaging the locking pawls and being positively moved by said armature into and out of locking position, a base frame, an ink pan mounted in said base frame so as to be 85 engaged by said time printing wheels when said reciprocating stamping frame is moved downwardly and supporting means for said ink pad allowing a short parallel downward motion of the pad together with 90 said printing wheels and hereupon a downward rotation of the pad to bring it out of the path of said downward moving stamping frame.

In testimony whereof I affix my signature.
PAUL MANSEL.
